PROCESS OF PRODUCING ARTIFICIAL SILK
FROM VISCOSETheodoor Kech, Arnhem, Netherlands, assignor
to American Enka Corporation, Enka, N. C., a
corporation of DelawareNo. Drawing. Application November 12, 1930,
Serial No. 495,289. In the Netherlands No-
vember 12, 1929

4 Claims. (Cl. 18—54)

My invention relates to a process for producing artificial silk from viscose in which strands are obtained having a more or less curled or crimped appearance. This property is of importance for certain purposes.

For the purpose of obtaining this desideratum it has already been proposed to subject artificial silk to an after-treatment in which the threads are first of all swollen by means of solutions capable of dissolving cellulose, whereupon the thread was caused to shrivel by means of other suitable liquids, and finally dried without being subjected to tension.

In contradistinction to this known process, the process according to my invention has the advantage that no special after-treatment is necessary, strands of artificial silk having a curled or crimped appearance being obtained by spinning in the normal manner.

According to my present invention a process is used therefor which is characterized by the feature that at least two bundles of filaments, which shrink to unequal extents, are united with one another.

Varieties of viscose of different quality (ripening, composition) may, according to my invention be spun in order to attain this purpose.

A number of spinning baths of different quality (composition, temperature, immersion length) may also be used according to my invention.

When employing the process according to my present invention at least two bundles of filaments, which have different shrinking capabilities, may be twisted together. The result is that the individual threads or filaments lie more loosely, so that the filament bundle obtains a bulky, curled appearance.

The so-called centrifuge process, as well as bobbin spinning may be used in my new process. In the latter case, however, the strands must be dried hanging freely.

As has already been remarked, for example two or more varieties of viscose may be spun in the same spinning bath and the coagulated filaments introduced together into a spinning pot. Instead of varieties of viscose of different composition, e. g., different cellulose content, viscose may also be used of different degrees of ripening, or even two identical kinds of viscose may be used, in which case certain substances are added to one of the two viscoses.

Another form of the process consists in using two or more different spinning baths with the same varieties of viscose. In this case the spinning baths may have different compositions, or

show differences in temperature, whilst different tensions also may be exerted on the two bundles of filaments, e. g., by using unequal immersion lengths.

Further, different varieties of viscose and unequal immersion lengths may be used.

The following examples are given for the purpose of explaining the invention.

Two varieties of viscose, one having a salt point of 5.5 and the other a salt point of 13, are spun from different spinning nozzles into a normal spinning bath containing 12% of sodium sulphate, 12% of magnesium sulphate and 10% of sulphuric acid. (The "salt point" of a viscose is the number which gives the percentage concentration of a sodium chloride solution in which a drop of viscose just flocculates).

The spinning is effected in the usual manner, the two filament bundles being led into a centrifuge pot together. As a result of the difference in salt point the individual filament bundles show a very different shrinking capacity and consequently a displacement of the individual filaments with respect to one another appears in the twisted thread, which gives rise to the curled appearance of the latter.

Example II.—Two varieties of viscose are used having different cellulose contents, e. g., spinning solutions having a cellulose content amounting to 8% and 5% respectively. Otherwise the procedure is as given in Example I.

Example III.—Two spinning baths arranged side by side are used in which the same varieties of viscose are spun in the usual manner. The composition of the two spinning baths may be chosen e. g. as follows:

1. 18% magnesium sulphate; 7% sodium sulphate; 1% zinc sulphate; 8% sulphuric acid.

2. 20% ammonium sulphate; 8% sulphuric acid. The filament bundles produced from these different spinning baths show very differently shrinking capabilities. These two filament bundles also are led into a single spinning pot and show a curled appearance after manufacture.

It is clear that the above examples come into consideration in differing aspects as regards variations in procedure. Thus, for example, instead of two, three or several filament bundles may be united and also varieties of viscose of different quality may be used in spinning baths of different composition or temperature. Besides leading into centrifuges, the thread bundles may also be commonly wound on a bobbin and subsequently twisted, equivalent results being attained thereby, pro-

vided only care is taken that the strands are dried while hanging freely.

I claim:

1. A process of producing crepe effect composite artificial silk yarns which comprises spinning concurrently at least two bundles of artificial silk filaments, uniting the said bundles of filaments by twisting the same and effecting a difference in the shrinking characteristics of the different bundles prior to collecting the twisted composite yarn.
- 10 2. A process according to claim 1 in which the difference in shrinking characteristics of the dif-

ferent bundles is effected by spinning concurrently different varieties of cellulose solutions.

3. A process according to claim 1 in which the difference in shrinking characteristics of the different bundles is effected by employing different quality spinning baths.

4. A process according to claim 1 in which the difference in shrinking characteristics of the different bundles is effected by subjecting the said different bundles to different spinning conditions after their extrusion but prior to collection.

THEODOOR KOCH.
